UNITED STATES PATENT OFFICE.

FRANK X. HEINDL, OF KERSEY, PENNSYLVANIA.

SAND-DRYING DEVICE.

1,424,904.

Specification of Letters Patent. Patented Aug. 8, 1922.

Application filed October 1, 1921. Serial No. 504,694.

To all whom it may concern:

Be it known that I, FRANK X. HEINDL, a citizen of the United States, residing at Kersey, in the county of Elk and State of Pennsylvania, have invented certain new and useful Improvements in Sand-Drying Devices, of which the following is a specification, reference being had to the accompanying drawings.

10 This invention relates to devices for drying granular material, particularly sand, and has for its object the provision of a device by means of which sand may be taken directly from a leaching or washing apparatus and dried effectively while it passes in a continuous stream or flow over drying means.

20 An important object is the provision of a device which is provided with means whereby the sand, or other material, will be caused to pass over a series of successive pans or chutes beneath which heating means is provided, the sand having its flow continuously by gravity and being discharged from the 25 device in a thoroughly dried condition.

Another object is the provision of interchangeable burner or steam heating means for applying the necessary heat to effect drying.

30 Still another object is the provision of a mechanism of this character which is closed so as to retain the heat therein and in which the chutes over which the sand passes are adjustable whereby to vary the angular incline thereof to insure proper feed of the 35 material.

An additional object is the provision of a device of this character which will be simple and inexpensive in construction, easy to use, 40 not likely to get out of order, efficient and positive in operation, durable and a general improvement in the art.

With the above and other objects and advantages in view, the invention consists in 45 the details of construction to be hereinafter more fully described and claimed, and illustrated in the accompanying drawings, in which:

Figure 1 is a perspective view of my device in closed position;

Figure 2 is a vertical sectional view therethrough;

Figure 3 is a detail view illustrating the adjustable mounting of the chutes;

Figure 4 is a detail view of one of the 55 heating burners;

Figure 5 is a detail perspective view of a steam heater; and

Figure 6 is a cross sectional view through 60 the device.

Referring more particularly to the drawings, I have shown my device as comprising an upright rectangular casing 10 of sheet metal which is reinforced internally with a plurality of angle iron supports 11 and 12, 65 the former being vertical and the latter being transversely arranged. The exact frame construction may of course be varied as may be found advisable in actual practice so as to provide a strong structure capable of 70 withstanding great strain. The casing 10 and frame therefor are mounted upon a suitable concrete base 13. One side of the casing is provided with doors 14 which may be opened to permit access to the interior for 75 the purpose of making adjustments and repairs. The casing is also provided in one side with an inlet opening 15 and at its opposite side with a discharge opening 16. It should also be stated that the top of the 80 casing is open.

Journalized transversely of the frame at the lower portion thereof adjacent the opening 15, is a shaft 17 which carries sprockets 18 about which are trained chains 19 which extend upwardly in a rearwardly inclined direction and which are trained about sprockets 20 secured upon a shaft 21 journaled at the open top of the frame. This shaft 21 carries a drive pulley or the like 22 by means 90 of which power may be applied for effecting movement of the chains 19. Carried by the chains is a series of spaced pockets 23 designed to be filled with sand which is shoveled or otherwise passed through the opening 95 15.

Located at the top of the frame is a hopper 24 into which the conveyor defined by the chains 19 and pockets 23 discharges and this hopper of course has an inclined bottom 100 provided with an opening. It is of course to be understood that if preferred sand to be dried might be passed directly into the hopper instead of being conveyed thereto by the elevator conveyor.

Disposed within the rear portion of the frame is a series of oppositely inclined chutes 25 which may be formed of sheet

- metal or any other construction and which are so arranged that the lower end of each will discharge into the upper end of the one next below, as clearly shown in Figure 2.
- 5 In some instances it may be found highly desirable that the angular incline of these chutes be varied and in order to effect this I make use of the adjusting means indicated at 26. The lower end of the lowermost chute extends to the discharge opening 16 while the upper end of the uppermost chute is located beneath the opening in the bottom of the hopper 24.

Extending vertically through the rear portion of the device is a pipe 27 adapted to conduct either steam or gas, as the case may be. Carried by this pipe and located beneath each chute 25 is a double burner 28 for the purpose of supplying flame against 20 the under sides of the chutes. These burners of course might be of any desired type and the illustration is more or less conventional.

In case gas is not available or if for any 25 reason its use is not desired, the pipe 27 may be used to conduct steam, in which event instead of the burners 28 I would make use of the steam heaters 29 which would be disposed below the chutes in place of the burners. The heaters 29 might be of varying 30 construction though I have illustrated them as consisting merely of a rather flat rectangular casing 30 provided at opposite corners with inlet and outlet pipes 31 and 32 and 35 having one side formed with a series of holes 33 through which steam may issue against the chutes.

In the use of the device sand to be dried, or in fact any other granular material, is 40 fed directly into the hopper 24 or else is shoveled or otherwise deposited on to the lower end of the conveyor through the opening 15. In this latter event the sand would be carried upwardly in the pockets 23 and 45 dumped either into the hopper 24 or on to the uppermost chute 25, depending upon the specific arrangement. In either event, the sand dropping on to the uppermost chute 25 will slide therealong on to the chute next below and so on until the sand completes the 50 circuit of all the chutes and is deposited through the discharge opening 16. Owing to the inclination of the chute it is apparent that the feed or flow of the sand will be 55 purely gravitational and will be insured continuously. As the sand passes over the successive chutes it is of course dried by the action of the gas burners or steam heaters, whichever would be used, so that when the 60 sand is finally discharged at the bottom of the device it will be in a thoroughly dry condition either for transportation, storage or use. Since the chutes 25 are pivotally connected to the frame through the medium of 65 the adjusting members 26 and these adjust-

ing members may be engaged in any desired pair of the series of openings with which they co-operate, it will be seen that by elevating or lowering a given adjustment 26 of one of the chutes all of the chutes above this 70 chute will have their angularity either lessened or greatened, dependent upon the direction of vertical adjustment of the adjusting members 26.

From the foregoing description and a 75 study of the drawings it will be apparent that I have thus provided a simply constructed device by means of which sand, and in fact many other materials not susceptible to injury by great heat, may be quickly and 80 easily dried while it is passing in a continuous stream or current and exposed to the action of heating means. It will be noted that two different feed means are provided whereby the sand may be led on to the uppermost drying chute, the means being selectively or simultaneously variable. It is likewise observable that owing to the adjustment which permits variation in the angular position of the chutes that they may be 85 arranged at whatever angle is found most advantageous for insuring gravitational flow of the material without danger of clogging.

While I have shown and described the preferred embodiment of the invention, it 95 is of course to be readily understood that I reserve the right to make such changes in the form, construction and arrangement of parts as will not depart from the spirit of the invention or the scope of the sub-joined 100 claims.

Having thus described my invention, I claim:

1. A device of the character described comprising an enclosed upright frame having an open top, an upwardly traveling conveyor extending along the forward portion of the frame, a series of oppositely inclined chutes mounted within the frame and pivotally connected therewith at their upper 105 ends and discharging into one another, the free ends of the chutes bearing upon the chute next below adjacent the pivoted end thereof, and heating means beneath each chute.

2. A device of the character described comprising an enclosed upright frame having an open top, an upwardly traveling conveyor extending along the forward portion of the frame, a series of oppositely inclined 110 chutes mounted within the frame and pivotally connected therewith at their upper ends and discharging into one another, the free ends of the chutes bearing upon the chute next below adjacent the pivoted end 120 thereof, and heating means beneath each chute, the pivotal connection of the upper ends of the chutes with the frame being adjustable.

3. A device of the character described 125

comprising an enclosed upright frame having an open top, an upwardly traveling conveyor extending along the forward portion of the frame, a series of oppositely inclined chutes mounted within the frame and pivotally connected therewith at their upper ends and discharging into one another, the free ends of the chutes bearing upon the chute

next below adjacent the pivoted end thereof, heating means beneath each chute, and means for independently vertically adjusting the pivotal connection of said chutes with said frame.

In testimony whereof I hereunto affix my signature.

FRANK X. HEINDL.
